Mehl and Helgare

UNITED STATES PATENT OFFICE.

ROBERT B. WOLPERT, OF MINNEAPOLIS MINNESOTA.

METALLIC BILLARD CUE.

Application filed April 13, 1925. Serial No. 22,618.

To all whom it may concern:

Be it known that I, ROBERT B. WOLPERT, a citizen of the United States, residing at Minneapolis, in the county of Hennepin and 5 State of Minnesota, have invented certain new and useful Improvements in Metallic Billiard Cues; and I do hereby declare the following to be a full, clear, and exact description of the invention, such as will enable others skilled in the art to which it 10 appertains to make and use the same.

My invention provides a metallic billiard cue having all of the desirable features and free from the defects of a wooden billiard 15 cue, and which, moreover, may be commercially made at comparatively small cost. Generally stated, the invention consists of the novel construction, combinations and arrangement of parts hereinafter described 20 and defined in the claims.

As is well known, a billiard cue must have increasing diameter toward its butt end. In practice, I have found it practically impossible or, at any rate, very expensive to 25 make metal billiard cues from tapered metal tubes. Such tapered metal tubes are not available as a commercial article nor can tapered metal tubes be readily rolled but must be cast. It is practically impossible to produce cast metal tubes in light form 30 with uniform walls. I have found that I can make a highly efficient billiard cue at very reasonably low cost by the use of a plurality of rolled metal truly cylindrical 35 tubes of different diameters and connecting such tubes by tapered reducing couplings. Moreover, these reducing couplings may be provided with counterbalancing ends or extremities capable of being readily cut off, 40 filed away or reduced so as to give the cue the desired balance.

In the accompanying drawings, which illustrate a billiard cue designed in accordance with my invention, like characters indicate like parts throughout the several 45 views.

Referring to the drawings:

Fig. 1 is a plan view showing the complete cue; and

Fig. 2 is a view, with parts broken away, showing the billiard cue with some parts sectioned and some parts in full plan and showing the said parts on a much larger scale than in Fig. 1.

The body portion of the cue illustrated is made up of three rolled metal tubes 3, 4 and

5, connected by tapered reducing couplings 6 and 7. Said tubes 3, 4 and 5 are of true cylindrical form and are of increasing diameter in the order named. The tube 3 is of the proper diameter for the tip end portion of the cue, while the tube 5 is of the proper diameter for the butt end of the cue. The tapered coupling 6, at its large end, 60 has a threaded shank 8 screwed into the adjacent end of the tube 4, and at its small end has a threaded shank 9 screwed into the adjacent end of the tube 3. Beyond the threaded shanks 8 and 9, said coupling is provided with reduced end portions 8^a and 9^a that serve as counterbalancing elements 65 and, as indicated, are adapted to be filed or cut away to give the cue its proper balance.

The coupling 7 is like the coupling 6, only larger in diameter. It is provided at its 70 large end with a threaded shank 10 screwed into the adjacent end of the tube 5 and is provided at its small end with a threaded shank 11 screwed into the adjacent end of the tube 4. Beyond the shanks 10 and 11, 75 said coupling is provided with reduced portions 10^a and 11^a, that also serve as counterbalances adapted to be filed or cut away more or less to give the cue its proper balance. In one instance in Fig. 2, a lock pin 80 or peg 12 is shown as driven into seats formed in the tube 5 and shank 10 to lock the coupling to the tube; and, of course, this scheme may be applied to the other threaded joints.

The cue tip 13 is shown as directly applied to a tip base or cap 14 having a threaded stud or shank 15 screwed into the tip end of the tube 3. The numeral 16 indicates a soft rubber bar or plug that is forced under some compression into the tube 3 and against the end of which the trunnion 15 is pressed. This pliable plug 16 serves to very considerably reduce the vibration in a cue and, hence, the noise produced in striking the billiard ball, and, of course, it also gives some weight to the tip end of the cue and is, therefore, an element in balancing the cue. Other non-resilient or sound-absorbing material may be used for this purpose, in lieu of the rubber plug.

The outer end of the tube 5 is closed by a plug or cap 17 working with screw-threaded engagement therein and preferably also provided with a reduced inner end portion 17^a adapted to be cut or filed away 100 more or less to vary the balance of the cue.

- Preferably, the cap 17, in its outer end, is formed with an annular dove-tailed seat that receives and holds a soft rubber buffer 18, which, if the cue be dropped onto the floor butt end downward, as is frequently the practice, will cushion the impact and deaden the sound.
- If desired, of course, the tapered coupling 6 may be made hollow to reduce the weight 10 of the tube. It will be noted that the couplings 6 and 7 are two truncated cones and that they blend smoothly into the adjacent ends of the cylindrical tips connected thereby.
- 15 In the use of the cue, the tube 8 will afford a handle, while the tube 3 will be moved over the guiding finger. In practice, I have found that there is an advantage in having the said tip end portion afforded 20 by the tube 3 of true cylindrical form, because the axis of the cue will not then be shifted laterally by the axial movement of the cue on the guiding finger or hand. From a manufacturing point of view, the 25 use of the true cylindrical tubes is of the utmost importance, for they may be commercially obtained at very reasonable cost, so that the cue made up thereof can be made up and sold at a price that will compete 30 with an ordinary wooden cue. Moreover, for reasons indicated, the cylindrical sections or tubes make a better cue than tapered sections or tubes. The tubes and couplings may be made of any suitable metal, but, 35 advisably, will be made of aluminum or some alloy of aluminum, which is of light weight as compared with the heavier metals. The exterior of the cue may be provided with any form of smooth surface finish, 40 but preferably would be given what is known as a "satin" or "dip" finish.
- What I claim is:
1. A billiard cue made up of a plurality of cylindrical sections progressively increasing in diameter from the tip toward the butt end and connected by tapered reducing couplings.
  2. A billiard cue made up of a plurality of cylindrical sections progressively increasing in diameter from the tip toward the butt end and connected by tapered reducing
- couplings, said couplings having threaded shanks screwed into the adjacent ends of said tubes.
3. A billiard cue made up of a plurality of cylindrical sections progressively increasing in diameter from the tip toward the butt end and connected by tapered reducing couplings, said couplings having threaded shanks screwed into the adjacent ends of said tubes, and certain of said shanks having reduced extensions adapted to be cut or filed away more or less to balance the cue.
4. A billiard cue made up of a plurality of cylindrical sections progressively increasing in diameter from the tip toward the butt end and connected by tapered reducing couplings, said couplings having threaded shanks screwed into the adjacent ends of said tubes; and a lock pin driven into seats formed in certain of said tubes and shanks to lock the same against relative rotation.
5. A billiard cue made up of a plurality of cylindrical sections progressively increasing in diameter from the tip toward the butt end and connected by tapered reduced couplings, a cue tip applied to the tip end of the smallest of said tubes, and a plug of vibration-reducing material inserted into the tip end of said small tube adjacent to said cue tip.
6. A billiard cue made up of a plurality of cylindrical sections progressively increasing in diameter from the tip toward the butt end and connected by tapered reducing couplings, and a plug screwed into the butt end of the largest of said tubes.
7. The structure defined in claim 6 in which said latter noted plug is provided with a reduced inner end portion adapted to be filed or cut away more or less to balance the cue.
8. The structure defined in claim 6 in which said latter noted plug is provided with a dove-tailed seat and a pliable cushion inserted in said seat and projecting axially outward of said plug.

In testimony whereof I affix my signature.

ROBERT B. WOLPERT.
